UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING MACHINE.

Application filed April 15, 1921. Serial No. 461,516.

To all whom it may concern:

Be it known that I, JOHN KIEWICZ, a citizen of the United States, and resident of Boston, county of Suffolk, State of Massachusetts, have invented an Improvement in Sewing Machines, of which the following description, in connection with the accompanying drawing, is a specification, like characters on the drawing representing like parts.

This invention relates to two-thread sewing machines of the type which are constructed to sew a short seam and then come to rest, such for instance, as a button-hole sewing machine, and it particularly relates to the means for pulling off a length of under thread at the end of the button-hole so as to provide a sufficient length of under thread for forming the first stitch on the next button-hole and for trimming the thread and stay cord.

One feature of the invention is a novel pull-off device which acts on the under thread between the throat plate and the tension for the under thread and which is operative to pull off a length of under thread through the tension while the last stitches are being formed on the button-hole, the amount of thread thus pulled off being sufficient to insure the proper formation of the first stitching at the beginning of the next button-hole.

Another feature of the invention is a novel thread trimming element which becomes operative after the stitch-forming mechanism has come to rest and after the above mentioned pull-off device has drawn off the length of under thread through the tension. The trimming device is constructed to draw through the throat plate the length of under thread which has been previously pulled through the tension by the pull-off and then to cut said under thread close to the work thereby leaving the necessary amount of under thread projecting through the throat plate to insure the proper formation of the first stitch on the next succeeding button-hole.

These two features of the invention cooperate to draw off the length of under thread in two stages, the first stage consisting in drawing the under thread through

the tension by the pull-off and the second stage consisting in drawing the pulled-off length of under thread through the throat plate. The advantage of this two stage operation is that it reduces to a minimum the liability of breaking or severing the under thread as it is drawn through the throat plate by the thread trimming device, for if the desired length of under thread were pulled off at one operation the tension on the thread would often be such as to cause the thread to break.

Another feature of my invention relates to a novel form of pull-off device which is mounted on the turret that supports the under thread mechanism and is operated by the turning movement of the turret during the formation of the barring stitches at the end of the button-hole. One advantage of this construction and operation is that the act of drawing the under thread through the tension while the last stitches are being formed results in providing an additional tension on the thread at the stitch-forming point so that the barring stitches are set more tightly than if the pulling-off operation were not being performed simultaneously with the formation of the stitches.

As stated above the thread-trimming device is constructed to draw through the throat plate a length of under thread before severing the thread and at the same time a length of stay cord is drawn through the throat plate leaving a sufficient length of stay cord projecting from the throat plate to insure the proper stitching operation at the beginning of the next button-hole. My improved thread trimmer operates at the end of the button-hole to cut not only the end of the stay cord extending to the source of supply but also the end of the stay cord which projects at the point where the stitching on the button-hole began.

In order to give an understanding of my invention I have illustrated it as it might be applied to a button-hole sewing machine of the "Reece" type, exemplifications of which are found in United States Patents No. 1,188,942, June 27, 1916, No. 1,188,944, June 27, 1916, No. 1,338,373, April 27, 1920, No. 1,361,871, Dec. 14, 1920, but inasmuch as the invention relates simply to the mecha-

nism for pulling off a length of under thread and trimming it and the stay cord I have shown in the drawings only such portions of a "Reece" button-hole sewing machine as are necessary to give an understanding of the invention.

In the drawings:

Fig. 1 is a side view of a portion of a button-hole sewing machine having my improvements applied thereto.

Fig. 2 is a front view of Fig. 1 with the overhanging arm omitted.

Fig. 3 is a plan view of the clamp plate and the portion of the bed frame showing my improved thread trimming device.

Fig. 4 is a section on the line 4—4, Fig. 3.

Fig. 5 is a section on the line 5—5, Fig. 3.

Fig. 6 is a section on the line 6—6, Fig. 3.

Fig. 7 is an enlarged horizontal view 20 through the turret.

Fig. 8 is a detail of the pull-off lever.

Fig. 9 is a view of a button-hole just at its completion and showing the threads which are trimmed by the mechanism herein described.

1 indicates a portion of the bed frame of a button-hole sewing machine from which rises the overhanging arm 2 carrying the upper thread-handling mechanism. Such mechanism comprises the usual needle bar 3 which supports the upper needle 4 which controls the upper thread 5, said needle bar having a vertical reciprocation in the overhanging arm as usual.

35 The under thread is indicated at 6 and it is manipulated by an under-thread-handling mechanism situated beneath the bed frame 1 and carried by a turret 7 which is rotatably mounted in bearings carried by 40 the depending portion 8 of the sewing machine frame. This turret as well as the upper needle is constructed to be rotated when sewing around the ends of the button-hole as usual in sewing machines of this type, and such rotation is herein provided for by the rock shaft 9 carrying the segment gears 10 that mesh with gears 11 and 12 on the needle bar 3 and turret 7 respectively, the rock shaft 9 being oscillated at the proper times 45 by the main cam 77 all as usual in button-hole sewing machines of this type.

50 The turret 7 is provided with the usual hollow spindle 72 through which the under thread 6 extends, said thread passing through a slot 13 formed in the spindle and around a tension 14 carried by the turret. From the tension the under thread passes through a guide eye 15 in the turret and thence extends to the needle of the under-thread-handling mechanism. The turret carries at its upper end the usual throat plate 16 which is situated beneath the sewing opening 17 in the clamp plate 18 that is movably carried by the bed frame 1 of the sewing machine. This clamp plate receives

the work *w* and the latter is held in position during the stitching on the button-hole by the usual clamps 19.

The parts thus far described are, or may be, all as usual in button-hole sewing machines and form no part of my present invention.

As stated above one feature of my invention relates to a novel pull-off device acting on the under thread 6 between the throat plate 16 and tension 14 and operating to draw off a length thereof from the source of supply while the last stitches are being formed on the button-hole, the length thus drawn off being sufficient to provide for the proper formation of the first stitch on the next button-hole. The length of thread thus drawn off between the throat plate 16 and tension 14 is subsequently drawn through the throat plate by the thread trimming device.

90 In my present invention this pull-off device is carried by the turret and is actuated to pull off the thread by the rotation of the turret which occurs when the last stitches on the button-hole are being formed.

95 The pull-off device is in the form of a lever 20 which is pivoted to a block 21 secured to the turret, said lever having at its upper end a guide eye 22 which is normally situated between the eye 15 in the turret and the tension 14 so that the portion of the under thread that extends between the tension and the guide eye 15 passes through the guide eye 22. This pull-off lever 20 is normally held in its operative position against a stop 23 by means of a spring 24. The lever is provided at its lower end with a finger 25 which is situated to be actuated by a cam 26 carried by the portion 8 of the frame.

100 During the stitching along the sides of the button-hole and around the eye end of the button-hole the turret will be so positioned that the finger 25 of the pull-off lever is out of engagement with the cam 26. When, however, the button-hole is just being completed the turret will be turned so as to cause the stitching to stitch across the end 127 of the button-hole. During this turning movement of the turret the finger 25 engages the cam 115 26 and causes the pull-off arm 20 to swing about its pivot thus drawing off a length of under thread between the tension 14 and the guide 15. This pulling off of a length of

120 under thread occurs while the stitches are being formed at the end of the button-hole and when the stitch-forming mechanism comes to rest the pull-off lever will be in its outward position shown in Fig. 1. This operation of drawing off a length of under thread occurs before the stitch-forming mechanism comes to rest and while the last stitches on the button-hole are being formed. This is an advantage because the tension caused by pulling off the length of under 130

thread augments the usual tension on the under thread so that the last stitches will be set tighter than would be the case if the under thread were subjected only to the tension produced by the tension device 14.

The stitch-forming mechanism comes to rest with the turret substantially in the position shown in Figs. 1, 2 and 7 and during the subsequent operation of the machine by 10 which the work is carried to button-hole-cutting position and the button-hole is cut the turret is reversed in its movement to carry the finger 25 out of engagement with the cam 26 thus allowing the pull-off finger to 15 be returned to its normal position.

My invention also includes a novel thread trimming device operating to draw through the throat plate the length of under thread which has been pulled off by the pull-off 20 lever 20 and also a length of stay cord 50 and then to trim the stay cord and thread close to the work after the stitch-forming mechanism has come to rest. These operations of drawing the under thread and stay 25 cord through the throat plate and trimming the latter is accomplished by a thread trimming member 27 which is pivoted at 28 to the clamp plate 18. This thread-cutting knife 27 is provided at its end with a notch 30 having a flaring throat 30. This cutter is situated above and close to the clamp plate 18 and is beneath the work. The notch is so 35 situated that as the trimmer swings from the full to the dotted line position the threads which extend from the work down through the throat plate, (such threads including the under thread, the stay cord which is laid around the edge of the button-hole, and also the loop of upper thread 40 extending from the work around the looper), will be gathered into the notch 29 and carried thereby laterally to one side of the throat plate thus drawing through the throat plate the length of under thread 45 which was pulled off by the lever 20 and also a length of stay cord, such threads and stay cord being cut close to the work after having been drawn through the throat plate. This cutting or trimming of the thread is 50 accomplished by the cooperation of a shearing plate 31 secured to the clamp plate 18 and provided with a shearing edge 32 situated at one side of the throat plate and against which the threads are carried by the 55 swinging movement of the member 27.

The notch 29 in the trimming member 27 is relatively narrow and the purpose of making it in this way is to prevent the possibility of the work or barring stitches being 60 cut by the thread trimming operation.

It will be understood that the thread trimming operation does not occur until after the stitch-forming mechanism has come to rest and the work clamps 19 have released 65 the work, and it will be also understood that

the member 27 swings beneath the work and in substantial contact therewith so that the threads will be engaged in the notch 29 at substantially the point where they leave the work. The work is normally in position so 70 that the point from which the threads extend downwardly is situated directly over the throat plate 16 and when the thread trimmer swings into the dotted line position it will carry the work laterally with it 75 after the threads have entered the notch 29. Such lateral movement of the work will draw the stay cord and under thread through the throat plate and the tension on the stay cord will tend to pull the work downwardly 80 against the upper side of the cutting element 27. The notch or slot 29 is so narrow, however, that the work will not be pulled down into it by the tension on the threads as they are pulled through the throat plate and therefore there is no danger that the work will be drawn downwardly by such tension 85 into a position where either the work or the barring stitches will be cut by the shear edge 32. This device therefore operates to cut 90 the threads close to the work without danger of injuring the button-hole stitching.

The thread trimming device is arranged to pass beneath the shear plate 31 and the latter is provided with a guiding finger 38 95 which rides up the inclined portion 39 of the member 27 and acts to guide the cutting member in its movement.

From the above description it will be obvious that when the threads are severed there 100 will be projecting from the throat plate not only a length of under thread but also a length of the stay cord. These ends will be left projecting from the work when the next button-hole is stitched so that at the completion 105 of the next button-hole there will be an end 41 of stay cord projecting from the under side of the work as shown in Fig. 9. The thread trimming device is constructed so that when it swings into the dotted line 110 position it will gather into the notch 29 not only the stay cord 50 extending from the work to the source of supply and the under thread but also the projecting end 41 of the stay cord and all these ends will be cut close 115 to the work thus making a finished button-hole.

The cutter 27 is provided with the inclined under face 42 which assists in guiding the end 41 of the stay cord into the notch 29. 120

The means herein provided for actuating the thread trimming member 27 is an actuating lever 33 pivoted to the machine frame at 34 and operated by a cam 35 rigid with the main cam all as shown in my Patent 125 No. 1,361,871, Dec. 14, 1920. The trimmer 27 is extended beyond the pivot 28 and is provided with a curved slot 34 forming on one side a cam face 35 and on the opposite side another cam face 36. The end of the 130

lever 33 stands vertically and is provided with a roll 37 which is situated to enter the slot 34 as the lever 33 is actuated.

I have herein provided a friction device 5 to apply sufficient friction to the cutter 27 to hold it in the full line position and while the lever 33 is disconnected from the slot 34. This frictional device is illustrated as a friction washer 40 which is confined between 10 the head of the pivot screw 28 and the member 27, said friction washer applying sufficient friction to the member 27 to insure its remaining in any position in which it may be left until it is positively actuated 15 by the lever 33.

I claim:

1. In a sewing machine constructed to sew a short seam and then come to rest, the combination with stitch-forming mechanism 20 constructed to concatenate an upper and an under thread, of a tension device for the under thread, and means operative during the formation of the final stitches of the seam and before the last stitch is begun to 25 draw a length of under thread from the source of supply through said tension device.

2. In a two-thread sewing machine constructed to sew a short seam and then come 30 to rest, the combination with stitch-forming mechanism constructed to concatenate an upper and an under thread, of a tension device for the under thread, means acting on the under thread while a plurality of 35 the final stitches of the seam are being made to draw through the tension device a length of under thread sufficient to insure the formation of the first stitch of the next seam.

3. In a sewing machine constructed to 40 sew a short seam and then come to rest, the combination with stitch-forming mechanism, of a tension device for the under thread, means operative during the formation of a plurality of the final stitches of the seam 45 to draw through the tension device a length of under thread, and means to cut the thread close to the work.

4. In a two-thread sewing machine constructed to sew a short seam and then come 50 to rest, the combination with stitch-forming mechanism constructed to concatenate an upper and an under thread, of a tension device for the under thread, means acting on the under thread and operative during the 55 formation of a plurality of the final stitches of the seam to draw through the tension device a length of under thread sufficient to insure the formation of the first stitch of the next seam, and means to cut the under thread close to the work.

5. In a button-hole sewing machine, the combination with stitch-forming mechanism including the under thread mechanism, of a rotatable turret on which said under 60 thread mechanism is supported, a thread

tension device on the turret, means to rotate the turret in sewing around the end of the button-hole, and means actuated by said rotation of the turret as the stitching on the button-hole is being completed to draw 70 through the tension device and from the source of supply a length of under thread sufficient to insure the proper formation of the first stitch on the next button-hole.

6. In a button-hole sewing machine, the 75 combination with stitch-forming mechanism including the under thread mechanism, of a rotatable turret on which said under thread mechanism is supported, means to rotate the turret in sewing around the end 80 of the button-hole, means actuated by the rotation of the turret to draw off a length of under thread from the source of supply during the formation of the last stitches on the button-hole and means to cut the thread 85 close to the work.

7. In a button-hole sewing machine, the 90 combination with a frame, of a turret rotatably mounted thereon, under thread manipulating mechanism carried by said turret, a pull off lever pivoted to said turret and acting on the under thread, and means to actuate said lever by the turning movement of the turret during the formation of the final stitches on the button-hole thereby 95 to pull off a length of under thread from the source of supply.

8. In a button-hole sewing machine, the 100 combination with a frame, of a turret rotatably mounted thereon, under thread manipulating mechanism carried by said turret, a pull off lever pivoted to said turret and acting on the under thread, and a cam carried by the frame and situated to engage 105 said lever as the turret turns during the formation of the final stitches of the button-hole thereby to draw off a length of under thread.

9. In a button-hole sewing machine, the 110 combination with a frame, of a turret rotatably mounted thereon and provided with a throat plate, under thread mechanism carried by the turret, a tension for the under thread mounted on the turret, means operative during the formation of the last stitches 115 of the button-hole to draw off a length of under thread between the throat plate and tension, means operative after the stitch-forming mechanism has come to rest to draw said length of under thread through the 120 throat plate and to cut it close to the work.

10. In a button-hole sewing machine, the 125 combination with a frame, of a turret rotatably mounted thereon and having a throat plate, under thread mechanism carried by the turret, a tension for the under thread, means to rotate the turret during the formation of the final stitches on the button-hole, means rendered operative by such rotation of the turret to draw off a length of under 130

- thread between the throat plate and tension, and means operative after the stitch-forming mechanism has come to rest to draw said length of under thread through the throat plate and sever the latter close to the work. 5
11. In a button-hole sewing machine, the combination with a frame, of a turret rotatably mounted thereon and having a throat plate, under thread mechanism carried by the turret, a tension for the under thread, means to rotate the turret during the formation of the final stitches on the button-hole, means rendered operative by such rotation of the turret to draw off a length of under thread between the throat plate and tension, and means operative to draw through the throat plate said length of under thread and a length of stay cord and to sever said thread and stay cord. 10
12. In a button-hole sewing machine, the combination with a frame, of a turret rotatably mounted thereon and provided with a throat plate, under thread mechanism carried by the turret, and tension for the under thread, means carried by the turret and operative during the formation of the last stitches to draw off a length of under thread between the throat plate and tension, means operative after the stitch-forming mechanism comes to rest to draw through the throat plate said length of under thread and a length of stay cord and to cut both close to the work. 15
13. In a two-thread button-hole sewing machine, the combination with work-holding means including a clamp plate on which the work is supported, of a throat plate beneath the clamp plate and through which the under thread passes, a shear plate stationarily carried by the clamp plate and situated at one side of the throat plate, a thread-trimming member pivoted to the clamp plate and operating between the shear plate and the clamp plate, said thread-trimming member having a notch which is arranged to receive the threads extending from beneath the work as said trimmer is moved toward the throat plate, and means to actuate said trimming member, the relative position of the shear plate and throat plate being such that the notched end of the thread-trimming member is carried across the throat plate in its travel toward the shear plate, whereby the threads gathered into the notch are drawn through the throat plate, said notch being relatively long and narrow and having sufficient width to receive the threads but of such narrow dimensions that the work cannot be drawn into it by the tension on the threads as said threads are being drawn through the throat plate. 20
14. In a sewing machine constructed to sew a short seam and then come to rest, the combination with stitch-forming mechanism, of means operative only during the formation of the final stitches of the seam and before the last stitch is begun to draw off a length of thread from the source of supply. 25
15. In a sewing machine constructed to sew a short seam and then come to rest, the combination with stitch-forming mechanism of means operative only during the formation of a plurality of the final stitches of the seam to draw off a length of thread from the source of supply, and means to cut the thread close to the work. 30

In testimony whereof, I have signed my name to this specification.

JOHN KIEWICZ.
